UNITED STATES PATENT OFFICE.

ANTON LAWRENCE OLSON, OF WELCH, MINNESOTA.

GARAGE-FLOOR.

1,378,483.

Specification of Letters Patent. Patented May 17, 1921.

Application filed January 22, 1920. Serial No. 353,293.

To all whom it may concern:

Be it known that I, ANTON LAWRENCE OLSON, a citizen of the United States, residing at Welch, in the county of Goodhue and 5 State of Minnesota, have invented new and useful Improvements in Garage-Floors, of which the following is a specification.

This invention relates to improvements in garage floors, the primary object being to 10 provide an improved structure wherein the floor can be easily and quickly converted into either a wash rack or into a smooth surfaced floor. As a result greater economy of 15 space in public garages is effected and in small garages greater facility is afforded for more efficiently caring for automobiles.

With these and other objects in view, my 20 invention comprises the features of construction and combination of parts hereinafter described and claimed.

In the accompanying drawing forming part of this specification, Figure 1 is a horizontal section of a garage, showing my improvement applied thereto; Fig. 2 is a section taken on the line 2—2 of Fig. 1; Fig. 3 is a section taken on the line 3—3 of Fig. 1; Fig. 4 is a section taken on the line 4—4 of Fig. 1, showing a detail; Fig. 5 is a section on line 5—5 of Fig. 1, showing a detail of 25 the floor in which the movable rack member is in raised or closed position; and Fig. 6 is a vertical section of a detail showing a modification of my invention.

In the drawing A indicates a garage floor 30 and its side walls having a doorway 11, all of usual form. The floor is constructed with a stationary grate C, made by molding metal or wooden grate bars 13 into the cement work of the floor or by forming said 35 bars out of cement integral with the floor. The spaces between these bars are formed with outwardly and downwardly flaring sides 14, resembling dove tail grooves and into these grooves are closely fitted a series 40 of upwardly and downwardly movable grate bars 15, which are designed to fill the spaces when in uppermost position and with the stationary grate form a smooth floor surface. These movable grate bars have outwardly and downwardly slanting sides 16, 45 corresponding with the sides of the stationary bars and are mounted upon inverted channel bars 17, thus forming a unitary movable structure. This structure is mounted 50 at each end upon eccentrics 18, projecting

into the channel bars, there being a series of eccentrics at one end mounted upon the shaft 19 and another series of eccentrics mounted at the other end on the shaft 20. These two shafts are journaled in the bearings 21 and 60 are revolved in unison by the main drive shaft 22, which is journaled in bearings 23 and connected with the eccentric shafts by pairs of intermeshing bevel gears 24. The drive shaft 22 is driven by a hand operable 65 lever 25 and reversible pawl and ratchet connection 26, which permits raising and lowering of the movable rack member according to which way the ratchet mechanism is connected to be operated.

Thus when it is desired to form a closed smooth surfaced floor or an open rack for washing purposes, the movable rack can be raised or lowered accordingly, by manipulating the handle 25. In use the automobile to 70 be washed is moved onto the grate C and the movable grate lowered. After washing the automobile the movable grate is raised into closing position to assist in forming a smooth 75 surfaced floor.

It is apparent that other means can be employed for raising and lowering the movable grate than that shown, and I do not wish to be understood that I confine myself to the 80 particular construction described.

One of these other forms is illustrated in Fig. 6, wherein a vertical toothed rack bar 30, depending from the movable rack member 15 is engaged by gearing 31, which is propelled by the screw pinion 32 on a driven 90 shaft 33. This driven shaft is operated by gearing 34, which in turn is operated by the separable hand operable shaft 35 from above the floor. As many sets of bars 30 and driving devices, actuated by shaft 33, 95 may be constructed below the movable rack member as desired.

Having described my invention what I claim as new and desire to secure by Letters Patent is:

1. In a device of the class described, the combination of a drain pit, a floor over the pit, said floor comprising a stationary draining rack and a movably disposed closure grate beneath the rack, said grate being 105 adapted, in one position, to obstruct the openings in the rack and supplement the support afforded thereby and, in another position, to clear the openings in said draining rack.

2. In a device of the class described, the combination of a drain pit, a floor over the pit, said floor comprising a stationary draining rack and a movably disposed closure 5 grate beneath the rack, said grate being adapted, in one position, to obstruct the openings in the rack and supplement the support afforded thereby and, in another position, to clear the openings in said draining 10 rack, and means for raising and lowering said closure rack.

3. In a device of the class described, the combination of a drain pit, a floor over the pit, said floor comprising a stationary draining rack and a movably disposed closure 15 grate beneath the rack, said grate being adapted, in one position, to obstruct the openings in the rack and supplement the support afforded thereby and, in another 20 position to clear the openings in said draining rack, eccentrics between said floor and bottom of the pit, upon which said closure grate is mounted and means for turning said

eccentrics to raise and lower the closure rack.

4. In a device of the class described, the combination of a drain pit, a floor over the pit, said floor comprising a stationary draining rack and a movably disposed closure 25 grate beneath the rack, said grate being 30 adapted, in one position, to obstruct the openings in the rack and supplement the support afforded thereby and, in another position, to clear the openings in said draining rack, said closure grate including spaced supporting members, a plurality of spaced eccentrics for each supporting member mounted 35 between said floor and bottom of the pit and adapted to carry said grate, and means for turning the eccentrics simultaneously in 40 reverse directions to raise and lower said closure rack.

In testimony whereof, I have signed my name to this specification.

ANTON LAWRENCE OLSON.
